UNITED STATES PATENT OFFICE.

EMILE MARTIN, OF OAKLAND, CALIFORNIA.

AUXILIARY-AIR-INLET AND MIXING DEVICE FOR INTERNAL-COMBUSTION ENGINES.

1,113,668.

Specification of Letters Patent. Patented Oct. 13, 1914.

Application filed January 3, 1914. Serial No. 810,146.

To all whom it may concern:

Be it known that I, EMILE MARTIN, a citizen of the United States, residing at Oakland, in the county of Alameda, State of California, have invented certain new and useful Improvements in Auxiliary-Air-Inlet and Mixing Devices for Internal-Combustion Engines; and I do hereby declare the following to be a full, clear, and exact description of the invention, such as will enable others skilled in the art to which it appertains to make and use the same.

This invention relates to auxiliary air inlet and mixing devices for internal combustion engines.

The object of the invention resides in the provision of a mixture feeding device which will thoroughly mix the gasoline with the air and in addition supply an auxiliary quantity of air to the mixture after it leaves the carburetor with resultant economy in the consumption of gasoline.

A further object of the invention resides in the provision of a device of the character named which will be simple in construction, efficient in use, and which may be manufactured at a comparatively small cost.

With the above and other objects in view the invention consists in the details of construction and in the arrangement and combination of parts to be hereinafter more fully described and particularly pointed out in the appended claims.

In describing the invention in detail reference will be had to the accompanying drawings wherein like characters of reference denote corresponding parts in the several views, and in which--

Figure 1. is a view in elevation showing the improved device operatively associated with the manifold and carburetor of an explosive engine; Fig. 2, a partial vertical section of what is shown in Fig. 1; Fig. 3, a view similar to Fig. 2 showing the position of the parts on the suction stroke of the engine; Fig. 4, a perspective view of the sliding piston employed in the device and which carries the rotary mixing screw and which controls the auxiliary air ports; Fig. 5, a perspective view disclosing the bridge carried at one end of the body of the device and which projects into the manifold; and Fig. 6, a section on the line 6-6 of Fig. 2.

Referring to the drawings the device is shown as comprising a tubular body por-

tion 10 having securing flanges 11 and 12 at respective ends thereof. These flanges 11 and 12 are attached through the medium of bolts 13 to flanges 14 and 15 respectively, the last named flanges being formed on the outer end of the manifold 16 and on the carburetor 17. By this construction it will be apparent that the device is incorporated in and forms a part of the connections between the carburetor and the explosion chamber of an engine. The body portion 10 is provided with a plurality of air ports 18 which are tapered in the direction of the flange 12.

Secured to the end of the body 10 adjacent the flange 11 is a bridge 19 which projects into the manifold 16 and extends transversely of the bore of the body 10. Mounted in the outer end of the bridge 19 is a screw 20 which has threaded thereon an adjusting nut 21 and a lock nut 22 for a purpose that will presently appear.

Slidably mounted in the bore of the body 10 is a tubular piston 23 having formed therein a slot 24 in which is engaged the end of a screw 25 threaded in the body 10 and whereby the sliding movement of the piston 23 in either direction is limited. This screw 25 also serves to lock the piston 23 against axial rotation as will be obvious. The end of the piston 23 adjacent the flange 12 is provided with recesses 26 corresponding in number and position to the air ports and adapted to register with said air ports to admit air to the interior of the piston when the latter is moved to its limit toward the flange 11.

Mounted upon the end of the piston 23 adjacent the flange 12 is a bridge 27, while a corresponding bridge 28 is mounted upon the end of the piston adjacent the flange 11.

Mounted upon the bridges 27 and 28 in the longitudinal axes of the piston are bearings 29 and 30 respectively and rotatably mounted in these bearings is an Archimedean screw 31 which is adapted to be rotated by the force of the air passing through the piston 23 on the suction stroke of the engine.

The end of the piston 23 adjacent the flange 11 is provided with an annular groove 32 in which seats the major end of a volute spring 33, the minor end of this spring receiving the screw 20 and bearing against the adjusting nut 21. It will be obvious that

2
this spring 33 constantly tends to maintain the piston 23 at the limit of its movement toward the flange 12 and in a position to close the air ports 18. It will be further apparent that by adjusting the nut 21 the normal tension of the spring 33 may be varied.

In the use of the device it will be apparent that upon the suction stroke of the engine the piston 23 will be moved against the influence of the spring 33 to the position shown in Fig. 3 and allow a certain quantity of air to be drawn through the air ports 18 into the bore of the piston 23 where it will mingle with the mixture coming from the carburetor and thoroughly mixed with the latter by the rotation of the screw 31, which rotation is induced by the force of the air moving through the bore of the piston 23. It will of course be understood that when the engine is running throttle down very little movement will be imparted to the piston 23 and hence very little air will be admitted through the auxiliary air ports 18. As the speed of the engine increases the movements of the piston 23 will become more pronounced until it eventually partakes of sufficient movement to completely uncover the air ports 18, at which time the supply of gasoline may be cut down with-

out in any manner impairing the efficiency 30 of the engine.

What is claimed is:

1. In a device of the class described, the combination of a tubular body having air ports therein, a tubular piston mounted for reciprocation in the bore of the body and yieldingly held against movement in position to close said air ports, and a rotary mixer mounted in the bore of the tubular piston. 40

2. In a device of the class described, the combination of a tubular body having air ports therein, a tubular piston mounted for reciprocation in the bore of the body, a bridge mounted on the body and extending across the bore thereof, a screw mounted on said bridge, a nut threaded on said screw, a spring having one end bearing against said nut and its other end against the tubular piston and yieldingly holding the piston in 50 position to close said air ports, and a rotary mixer mounted in the bore of the piston. 45

In testimony whereof, I affix my signature, in the presence of two witnesses.

EMILE MAITRE.
